UNITED STATES PATENT OFFICE

JOHN E. LAWTON, OF COUDERSPORT, PENNSYLVANIA

FLYER FOR SILK SPINNING MACHINES

Application filed March 6, 1929. Serial No. 344,771.

This invention relates to flyers for silk spinning machines, and has for one of its objects to provide a device of this character which will embody comparatively few parts 5 of simple construction and capable of being manufactured and assembled in a comparatively short time and at little expense.

The invention has for a further object to provide a flyer which will embody an 10 anchoring sleeve provided with an outer annular shoulder, and a spring secured within the sleeve and adapted to retain it upon a spindle against accidental displacement.

15 The invention has for a further object to provide a flyer which will embody a journal sleeve adapted to be supported upon the anchoring sleeve by said shoulder and retained upon the anchoring sleeve by said 20 spring.

The invention has for a further object to provide a flyer which will embody a base plate adapted to be rotatably supported upon the journal sleeve by outer shoulders 25 formed upon said sleeve and contacting with the upper and lower sides of said base plate.

The invention has for a still further object to provide a flyer wherein the base plate shall be provided with means adapted to 30 permit the flyer wires to be secured thereto easily and quickly and in a firm manner.

With the foregoing and other objects in view, the nature of which will appear as the description proceeds, the invention consists in the construction, combination and arrangement of parts hereinafter fully described and claimed, and illustrated in the accompanying drawing, wherein:

Figure 1 is a view in side elevation of 40 the flyer applied to a spindle of a spinning machine;

Figure 2 is a top plan view of the flyer;

Figure 3 is a sectional view on an enlarged scale taken on the plane indicated 45 by the line 3-3 of Figure 2;

Figure 4 is a sectional view taken on the plane indicated by the line 4-4 of Figure 3;

Figure 5 is a sectional view taken on the 50 plane indicated by the line 5-5 of Figure 3;

Figure 6 is a view in side elevation of the anchoring sleeve of the flyer;

Figure 7 is a view in side elevation of the journal sleeve of the flyer;

Figure 8 is a perspective view of the right 55 twist flyer wire, and

Figure 9 is a similar view of the left twist flyer wire.

Referring in detail to the drawing, 1 designates one of the upright spindles of a 60 spinning machine, 2 a bobbin mounted upon the spindle, and 3 the flyer.

The flyer 3 comprises an anchoring sleeve 4 which is mounted upon the spindle above the bobbin 2. A vertical slot 5 is formed in the lower end portion of the anchoring sleeve 4, and circumferentially spaced vertical slots 6 and 7 are formed in the upper end portion of the sleeve. The slots 5, 6 and 7 are closed at their ends, and the lower 70 slot 5 is arranged in a vertical plan passing centrally between the upper slots 6 and 7. An outwardly extending shoulder 8 of annular formation, is formed upon the anchoring sleeve 4 between the horizontal center 75 of the sleeve and the slot 5.

A journal sleeve 9 which is split longitudinally, is supported upon the anchoring sleeve 4 by the shoulder 8. The journal sleeve 9 is provided at opposite sides of its 80 horizontal center with outwardly extending shoulders 10 and 11 of annular formation.

A base plate 12 having a substantially circular central portion or hub 13, and arms 14 extending in opposite directions from 85 the hub and increasing in width in the direction of their outer ends, is provided in its hub with an opening 15 for the reception of the journal sleeve 9. The base plate 12 is rotatably supported on the journal sleeve 9 by the shoulders 10 and 11 which contact with the upper and lower sides of the hub 13. The arms 14 are provided at their inner ends with openings 16, and are provided at their outer ends with 95 longitudinally spaced pairs of retaining elements or clips 17. The right twist flyer wire 18 and the left twist flyer wire 18^a are of V-form, and are arranged upon the arms 14 with their apexes innermost. The apex 100

portions 19 of the flyer wires 18 and 18^a extend downwardly and inwardly through the openings 16 and engage projections 16^a extending outwardly from the inner walls of the openings 16.

The sides of the flyer wires 18 and 18^a are arranged beneath the clips 17, which are formed integrally with the arms 14. One side of each flyer wire terminates in a thread 10 engaging eye 20, and the other sides thereof are provided with downwardly extending arms 21 terminally provided with thread engaging eyes 22. The eyes 20 and 22 of each flyer wire are arranged in parallel vertical 15 planes.

A spiraled spring 23 tapering in the direction of its upper end and made from flat stock, is arranged within the anchoring sleeve 4. The spring 23 receives the spindle 20 1, and during the application of the flyer to the spindle the spring is tensioned so as to establish sufficient friction between it and the spindle to hold the flyer against accidental displacement. The spring 23 is connected to the anchoring sleeve 4 in a manner to prevent the anchoring sleeve from having any rotary movement with respect thereto. This connection is established by passing the lower end of the spring through 25 the slot 5 and bending it into contact with the outer side of the anchoring sleeve, as shown at 24, and by passing the upper end portion of a spring through the slot 6, bending said end portion about the outer side of 30 the anchoring sleeve, as shown at 25, and by then carrying the free end of the spring back into the anchoring sleeve through the slot 7, as shown at 26. The spring portion 35 lies against the outer side of the anchoring sleeve 4 above the journal sleeve 9, and serves to maintain the journal sleeve on the anchoring sleeve.

In practice, the journal sleeve 9 and base plate 12 are first assembled, and this may be 45 readily done since the journal sleeve is split longitudinally. These assembled parts are then applied to the anchoring sleeve 4, and this is done by sliding the journal sleeve 9 upon the anchoring sleeve until it contacts 50 with the shoulder 8. The spring 23 is then inserted in the anchoring sleeve 4 and connected therewith in the manner stated. If desired, the flyer wires 18 and 18^a may be applied to the base plate 12 before or after 55 the application of the base plate to the journal sleeve 9. To connect the flyer wires 18 and 18^a to the base plate 12, it is only necessary to engage the angular ends 19 of the flyer wires with the projections 16^a of the 60 base plate, swing the flyer wires into contact with the upper sides of the arms 14, and then bend the clips 17 into contact with the sides of the flyer wires. It will be understood that the parts of the devices are 65 connected together in a very simple manner

and in a manner to prevent their accidental separation.

While I have described the principle of operation of the invention, together with the device which I now consider to be the best embodiment thereof, I desire to have it understood that the device shown is merely illustrative, and that such changes may be made when desired as are within the scope of the invention as claimed.

What I claim is:

1. A flyer comprising an anchoring sleeve, flyer wires, means adapted to rotatably connect the flyer wires to the sleeve, and a spiral spring arranged within the sleeve and having its ends secured thereto and adapted to frictionally engage a spindle.

2. A flyer comprising an anchoring sleeve, provided with a shoulder, a journal sleeve surrounding the anchoring sleeve and resting upon the shoulder, a spindle receiving spring arranged within the anchoring sleeve and secured thereto with a portion arranged outside the sleeve above the journal sleeve, a base plate connected to the journal sleeve, and flyer wires connected to the base plate.

3. A flyer comprising an anchoring sleeve provided in its lower end portion with a slot and in its upper end portion with a pair of slots, the sleeve being provided between said first slot and said second slots with an outer shoulder, a journal sleeve surrounding the anchoring sleeve and resting upon the shoulder, a spindle receiving spring arranged within the anchoring sleeve and having its lower end passed through said first slot and having its upper end passed through said second slots with a portion thereof arranged outwardly of the anchoring sleeve and above the journal sleeve, a base plate connected to the journal sleeve, and flyer wires connected to the base plate.

4. A flyer comprising a journal sleeve provided with vertically spaced and outwardly extending shoulders, a base plate having a hub arranged between said shoulders and provided with arms having openings and clips, and flyer wires engaged by said clips and having angular portions extending through the said openings.

5. A flyer comprising a base plate provided with inner openings and outer clips, and flyer wires of V-form having their inner ends extending downwardly and inwardly through said openings and having their sides engaged by said clips.

6. A flyer comprising a base plate provided with openings, flyer wires connected to the base plate and having angular ends passing through said openings, and projections carried by the base plate and engaging the angular ends of the flyer wires.

7. A flyer comprising right and left flyer wires, each wire embodying two sides, one side terminating in a thread engaging eye,

the other side terminating in a downwardly extending arm which in turn terminates in a thread engaging eye, a base plate provided with openings, said flyer wires connected to said base plate and having angular ends passing through said openings, as and for the purposes set forth.

8. A flyer comprising right and left flyer wires, each wire embodying two sides, one side terminating in a thread engaging eye, the other side terminating in a downwardly extending arm which in turn terminates in a thread engaging eye, a base plate provided with openings, said flyer wires connected to said base plate and having angular ends passing through said openings, and projections carried by said base plate and engaging the angular ends of the flyer wires, as and for the purposes set forth.

10 9. A flyer comprising an anchoring sleeve, flyer wires, means adapted to rotatably connect the flyer wires to the sleeve, and a spiral spring arranged within the sleeve and having its ends secured thereto, said spring tapering in the direction of its upper end and adapted to frictionally engage a spindle, as and for the purposes set forth.

15 10. A flyer comprising a base plate provided with pairs of oppositely extending projections, and a flyer wire resting upon the base plate and said oppositely extending projections engaging said wire for retaining the wire in engagement with said base plate.

20 In testimony whereof I affix my signature.
JOHN E. LAWTON.
